UNITED STATES PATENT OFFICE.

JOHN CAMPBELL, OF WALDEN, NEW YORK.

BENCH-PLANE.

SPECIFICATION forming part of Letters Patent No. 271,219, dated January 30, 1883.

Application filed August 9, 1882. (No model.)

To all whom it may concern:

Be it known that I, JOHN CAMPBELL, of 5
Sheffield, England, and a resident of Walden,
in the town of Montgomery, in the county of
Orange and State of New York, have invented
certain new and useful Improvements in Planes;
and I do hereby declare the following to be a
full, clear, and exact description of the invention,
such as will enable others skilled in the
art to which it pertains to make and use the
same.

My invention relates to planes, the object
being to provide a plane adapted for use either
as a chamfer or smoothing plane, of such con- 15
struction as to be readily adjusted.

The invention consists in the peculiar con-
struction and combinations of parts hereinafter
described, and pointed out in the claim.

In the drawings, Figure 1 represents a per- 20
spective view of my improvement, and Fig. 2
is a view of the parts detached.

A represents the stock of the plane, consisting
of the sole *a* and sides *a'* *a''*. The sole is
provided at its forward end with a slot, *B*, and
beveled seat *b* for the point of the bit. The bit
or plane-iron *C* is adapted to project under a
rod, *c*, set into the sides of the stock, and to 25
rest on a beveled bed or rest, *D*. A wedge,
E, is then forced under the rod *c*, and is held
in place by a screw, *e*, provided with a disk or
head, *e'*, which bears against the upper end of
the bit. The upper end of the wedge *E* is 30
rounded and curved to form a bearing, *e''*, for
the hand or fingers, and is provided with a cen-
tral screw-threaded perforation, *e'*, adapted to
receive the screw *e*. This wedge *E* is also pro-
vided with upwardly-projecting side ears, *d*,

which latter are centrally grooved for the pur-
pose of preventing the wedge from rising up
when secured in place. When the wedge is 40
unscrewed, the bit is firmly clamped, while by
turning the screw into the perforation of the
wedge the bit is loosened and may be removed.

The sole *a* of the stock is provided with a
second slot, *F*, just in rear of the rest *D*, while 45
a rod, *G*, is secured between the sides in rear
of the slot *F*, and two projecting beveled rests,
H, are provided adjacent to the rod. Thus it
will be seen that the bit may be secured at the
forward end of the stock to form a chamfer- 50
plane, or at the center to form a smoothing-
plane.

The parts are simple in construction, easily
manipulated, and adapted to be durable and
efficient in use.

Having fully described my invention, what I
claim as new, and desire to secure by Letters
Patent, is—

The combination, with the stock provided
with two transverse slots, one of which latter 60
is situated near the extreme front end thereof,
the beveled rests *D* and *H*, and the transverse
rods *c* and *G*, of the removable bit, the wedge
E, having the slotted side ears, *d*, and the fast-
ening-screw, all of the above parts combined 65
and adapted for the purpose set forth.

In testimony whereof I have signed this
specification in the presence of two subscrib-
ing witnesses.

JOHN CAMPBELL.
